(57) **CLAIM**

The ornamental design for a vehicle interior storage unit, as shown and described.

DESCRIPTION

FIG. 1 is a front, top, and right-side perspective view of a vehicle interior storage unit showing the new design; FIG. 2 is a rear, bottom, and left-side perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is a front, top, and right-side perspective view thereof, where the vehicle interior storage unit is in use. The broken lines showing portions of the vehicle interior storage unit are included for the purpose of illustrating environmental structure and form no part of the claimed design.

1 Claim, 7 Drawing Sheets
